FEEDER FOR ABRASIVES

Jacob Soderberg, Pittsburgh, Pa., assignor to
Pittsburgh Plate Glass Company, a corporation
of Pennsylvania

Application November 26, 1932
Serial No. 644,413

5 Claims. (Cl. 51—263)

The invention relates to apparatus for feeding a mixture of abrasive (ordinary sand) and water to a grading apparatus, the particular use shown being the supply of the mixture to a grading system where the abrasive is used in grinding the edges of heavy glass plates, but the invention is of more general application and may be employed in any relation in which it is desired to feed abrasive and water from storage to a point of use. In a grading system for use in grinding plate glass, it is necessary to supply new coarse abrasive to the system as the material in use is gradually broken up and reduced in size, which calls for replenishment of the coarser grades. It is desirable that this supply should be constant rather than intermittent as an intermittent or irregular supply of abrasive adversely affects the grading operations, but it has been difficult to secure such a supply as the amount of new abrasive supplied is relatively small and with a small flow of the mixture, there is a constant tendency of the material to clog in the supply pipes. The present invention is designed to overcome this difficulty and provide means for accomplishing the feed which permits such feed to be as small as may be desired without any danger of clogging and which is subject to an adjustment so that exactly the right amount of abrasive is accurately supplied to meet any requirement. The desired result is accomplished by the use of special valve which is opened at predetermined intervals by a continuously operated motor so that the flow of abrasive mixture when it does occur is of relatively large volume, thus washing out any abrasive which may settle in the supply pipe and tend to cause clogging. One embodiment of the invention is illustrated in the accompanying drawings, wherein:

Figure 1 is a side elevation showing the general arrangement of the apparatus as applied to a glass grinding system employing a rub bed. Fig. 2 is a side elevation of the apparatus on a larger scale than that of Fig. 1. And Figs. 3, 4 and 5 are enlarged detail views, Fig. 3 being a plan view, Fig. 4 a section on the line IV—IV of Fig. 3, and Fig. 5 a side elevation.

Referring to the drawings, 1 is a sand and water storage receptacle having a rubber conduit or hose 2 leading to the hopper 3 which in turn discharges to a sump 4 through the conduit 5. The mixture of sand and water in the sump is carried up into the grading tank 6 by the pump 7, and the finer sand, eliminated over the upper edge by the upflow of water through the tank. The coarse sand which is required for the grind-

ing operation is supplied through the pipe 8 to the sand box 9 and thence discharges upon the rotating table or rub bed 10, the heavy glass sheets whose edges are to be ground being supported in vertical position so that their lower edges engage the table, this being a procedure well known in the art. The waste water and sand which flows from the table is caught in a gutter and conducted through the pipe 11 to the sump. This used sand is again carried up into the grader and the part thereof which is coarse enough to use, is again removed through the pipe 8, the remainder of the sand, which is too fine for use to advantage being removed over the top of the tank as herebefore pointed out.

The apparatus, to which the invention here particularly relates, comprises means for controlling the flow of abrasive and water from the storage tank 1 through the conduit or hose 2 and will be understood by reference to Figs. 2 to 5. This apparatus includes a bracket 12 which is bolted to the top of the hopper 3 and has a flat plate 13 lying against one side of the rubber conduit 2. Extending longitudinally of the bracket is a shaft 14 mounted in suitable bearings on the bracket and carrying a pair of arms 15, between which is mounted a rod 16, which engages the conduit opposite to the plate 13, and closes it when the parts are in the position shown in Fig. 4. The parts are normally held yieldingly in this position by means of a crank arm 17, keyed to the end of the shaft 14, and by the weight 18 carried on the end of the crank arm.

The crank arm also carries a block 19 mounted on stud bolts 20 so as to permit of rocking movement, and through the block extends a connecting rod 21 which is screw threaded and carries a sleeve 22 which is freely slidable in the block. The lower end of the sleeve is seated in and secured to the knurled knob 23 which acts as a stop member, as later described. By rotating the knob, the sleeve may be adjusted up and down on the rod. It is locked in position by the thumb screw 24. The upper end of the rod 21 is pivoted to a crank 25 and the crank is rotated to reciprocate the rod by means of a motor 26 operating through suitable reduction gearing in the casings 27 and 28.

On the upward movement of the rod 21, the stop 23 engages the block 19 and raises the weighted lever 17, thus rocking the shaft 14, and causing the rod 16, which engages the conduit 2 and clamps it shut, to move back from such conduit, so that by gravity a quantity of the abrasive mixture is discharged to the hopper 3 beneath. On the downward movement of the rod 21, the stop

23 moves down, permitting the weight 18 to move the lever arm downward, thus moving the rod 16 back to the position shown, at which time it clamps the conduit 2 against the plate 13 and 5 closes it. By adjusting the position of the sleeve 22 longitudinally of the rod 21, the amount of opening of the conduit during the reciprocation of the rod is regulated. This provides a very close adjustment of the abrasive supply, and permits 10 the supply of as small a quantity of abrasive as may be needed without any danger of clogging the conduits leading to the grading system such as occurs due to settling when a small quantity of the mixture is fed continuously through the 15 conduits. The larger flow for short intervals as here provided keeps the conduits washed clean and avoids inconvenience due to stoppage. The smooth interior of the hose also tends to prevent clogging and the weight 18 may be adjusted so as 20 to positively close the conduit without the application of such pressure as might cut or injure the hose. The apparatus will function indefinitely without attention and without any requirement for replacement or repair.

25 What I claim is:

1. Apparatus for supplying a mixture of abrasive and water from a storage receptacle to a grading system, comprising a conduit of flexible material, means for yieldingly compressing the conduit to 30 close it, a continuously operating motor and a lost motion connection between said means and the motor whereby said means is intermittently moved to position to permit the conduit to open.

35 2. Apparatus for supplying a mixture of abrasive and water from a storage receptacle to a grading system, comprising a conduit of flexible material, a clamping member for compressing the conduit to close it, means normally applying yielding force 40 to move the clamping member to a position closing the conduit, a continuously operating motor, a connecting rod which is reciprocated back and forth by the motor, and a lost motion connection between the clamping means and the connecting 45 rod for moving the clamping means to position

permitting the conduit to open upon each reciprocation of the connecting rod.

3. Apparatus for supplying a mixture of abrasive and water from a storage receptacle to a grading system, comprising a conduit of flexible material, 80 means for yieldingly compressing the conduit to close it, a continuously operating motor, a lost motion connection between said means and the motor whereby said means is intermittently moved to position to permit the conduit to open, and means for adjusting the lost motion in said connection to regulate the degree of opening of the conduit by said connection.

4. Apparatus for supplying a mixture of abrasive and water from a storage receptacle to a grading system, comprising a conduit of flexible material, a clamping member for compressing the conduit to close it, means normally applying yielding force to move the clamping member to a position closing the conduit, a continuously operating motor, a connecting rod which is reciprocated back and forth by the motor, a lost motion connection between the clamping means and said rod for moving the clamping means to position permitting the conduit to open upon each reciprocation of the rod, and adjusting means whereby the lost motion in said connection may be adjusted to regulate the degree of opening of the conduit by said connection.

5. Apparatus for supplying a mixture of abrasive and water from a storage receptacle to a grading system, comprising a conduit of flexible material, a clamping member for compressing the conduit to close it, means normally applying yielding force to move the clamping member to a position closing the conduit, a continuously operating motor, a connecting rod which is reciprocated back and forth by the motor, a crank connected to the clamping member comprising an arm through which the rod slides freely, and an adjustable stop on the rod on one side of said arm adapted when the rod moves in one direction to swing the said arm to cause the clamping means to move so as to permit the conduit to open.
